[57] CLAIM

The ornamental design for a stacking container for baked goods, as shown and described.

DESCRIPTION

FIG. 1 is a perspective view of a stacking container for baked goods showing my new design;

FIG. 2 is a perspective view thereof showing the cover in the open position;

FIG. 3 is a rear view thereof;

FIG. 4 is a rear view thereof with the cover in the open position;

FIG. 5 is a left side view thereof;

FIG. 6 is a left side view thereof with the cover in the open position;

FIG. 7 is a top plan view thereof; and,

FIG. 8 is a bottom plan view thereof.

The side opposite to that shown in FIGS. 5 and 6 is a mirror image thereof.
